UNITED STATES PATENT OFFICE.

LEWIS M. CLEMENT, OF NEWARK, NEW JERSEY, ASSIGNOR TO WESTERN ELECTRIC COMPANY, INCORPORATED, OF NEW YORK, N. Y., A CORPORATION OF NEW YORK.

OSCILLATION-GENERATING SYSTEM.

1,395,390.

Specification of Letters Patent.

Patented Nov. 1, 1921.

Application filed September 30, 1918. Serial No. 256,247.

To all whom it may concern:

Be it known that I, LEWIS M. CLEMENT, a citizen of the United States, residing at Newark, in the county of Essex, State of New Jersey, have invented certain new and useful Improvements in Oscillation-Generating Systems, of which the following is a full, clear, concise, and exact description.

This invention relates to electrical oscillation generators and is adapted for use in connection with signaling and other transmission systems wherein there is used an audion or equivalent electrical discharge device for generating high frequency oscillations.

An object of the invention is to provide means for varying the frequency of an oscillator and simultaneously to automatically provide the proper plate coupling and feed-back coupling for any particular frequency at which the oscillator is set to oscillate.

A further object is to provide a means suitable for use in signaling and other transmission systems for quickly changing the wave length, preferably by a single adjustment by the operator, whereby greater secrecy can be secured and interference avoided.

Heretofore, in using certain transmitting systems employing a high frequency generator of the audion type when it was desired to change the wave length on which the signal was being transmitted, it was necessary to perform several operations to adjust the wave length, the coupling of the plate circuit to the oscillation circuit and the coupling of the grid or input circuit to the oscillation circuit, as changes of one of these

usually affected the others and after each change of wave length a series of adjustments would be necessary before transmission could recommence. This invention is intended to prevent this loss of time and furthermore to simplify the necessary operations that much less skill is required on the part of operators than has heretofore been the case.

The invention is shown in the accompanying drawings wherein Figure 1 is a diagram of a system involving the invention,

Fig. 2 is a detail view of a clip connector for making a variable connection to the spiral winding induction coil hereinafter described.

55

In the system shown in Fig. 1 a tuned, oscillatory, antenna circuit includes aerial 1, coil 2, coil 3 and condenser 4, and is grounded at 5. The vacuum tube or audion 6 generates oscillations directly in the antenna circuit being connected thereto by an anode connection 7, grid connection 8 and cathode connection 9. A leak resistance r is shunted across the grid and filament connections. The tube 6 is preferably of the highly evacuated type, the operation of which does not depend upon gas ionization. A switch shaft 10 carries contact arms 11, 12, 13 and 14 which engage respectively series of contact elements 15, 16, 17 and 18. 70 Elements 15 and 16 are connected to various points in coil 2, as shown, while elements 17 are connected by leads 19 to coil 3 which may conveniently be a strip of metal wound in a spiral. For fine adjustments on coil 3 the leads 19 may be flexible and terminate in clips or equivalent devices 20 (Figs. 1 and 2). A much finer adjustment can be secured in this manner than is possible where the smallest variation corresponds to 80 a whole turn of a coil. In one form the body 21 of device 20 consists of insulating material and contains a spring contact member 22 which is held by screw 23 and is adapted to clamp upon member 3. Lead 85 19 is connected to screw 23. Contact elements 18 are each connected to one of a set of capacities 4' which are selectively in parallel with capacity 4. Capacities 4 and 4' may each be made variable if desired. 90

In operation, a change of wave length will be accomplished by changing the switch 10 from one position to another. This causes a simultaneous change in the value of the inductances 2 and 3 connected in the 95 circuit between the anode lead 7 and the cathode lead 9 to device 6 and likewise a change in the value of capacity connected between the grid lead 8 and cathode lead 9 of device 6. The apparatus is preferably 100 adjusted for maximum efficiency at each wave length on which it is desired to trans-

mit signals. The wave length will depend upon all the constants of the oscillatory antenna circuit; the plate coupling will be determined by the nature and magnitude of 5 the portion of the oscillatory circuit between leads 7 and 9; and the grid or input coupling by the nature and magnitude of the elements of the oscillatory circuit which are between the leads 8 and 9. By plate coupling 10 is understood the coupling between the cathode-anode or plate circuit of the tube and the antenna circuit. By means of the connectors 20 a very exact adjustment for wave length may be made at any time. A 15 number of different wave lengths will be available, five in the present instance, and the operator can switch from one to the other instantly. No adjustment need be made other than a single movement of a 20 single switch. The advantages of such an arrangement will be apparent to those skilled in the art.

In order to illustrate a complete system the associated tube 24 with input circuit 25, 25 which is coupled to microphone circuit 26, are shown. These parts together with choke coil 27, high frequency choke coil 28, and battery 29 coöperate with the oscillator system and function to produce modulated 30 signaling waves in the antenna, since the amplitude of the oscillations generated in the antenna circuit will vary in accordance with variations of impedance of tube 24 which in turn varies in accordance with sound waves 35 acting upon the microphone.

The particular means described herein are not essential to carrying out the invention as many modifications in arrangement and design will be apparent to those skilled in 40 radio telephony. The generic and specific features of novelty of the invention are defined in the claims.

What is claimed is:

1. In combination, a circuit, a pair of 45 circuits coupled thereto, means for transferring wave energy from one of said pair of circuits to said first-named circuit, means for transferring wave energy from said first-named circuit to the other of said pair of 50 circuits, and a common means for changing the tuning of said first-named circuit and simultaneously changing the couplings of said pair of circuits to a different value than would result from the change of tuning 55 alone.

2. In combination, a tuned circuit, a pair 60 of circuits coupled thereto, means for transferring wave energy from one of said pair of circuits to said tuned circuit, means for transferring wave energy from said tuned circuit to the other of said pair of circuits, a moveable element, and means operable by a single displacement of said element for changing the tuning of said tuned circuit 65 and simultaneously changing the couplings

of said coupled circuits to a different value than would result from the change of tuning alone.

3. In combination, an antenna circuit, an electric discharge device, means including 70 circuit arrangements whereby said discharge device works directly into said antenna circuit to produce oscillations therein, and means operable by a single movement whereby the period of said antenna circuit 75 is changed and the circuits connecting said discharge device to said antenna circuit are modified for approximately maximum operating efficiency.

4. In combination, a thermionic discharge 80 tube, an antenna circuit, input and output circuits for said tube each having a coupling to said antenna circuit, distinct means for varying the period of said antenna circuit and each of said couplings, a common 85 operating means for said distinct means whereby each of said couplings and the period of said antenna circuit are adjustable to several values mutually adapted to one another.

5. In combination, a vacuum tube, means including circuits associated with said tube whereby it functions as an oscillation generator, said circuits including a tuned circuit, an input circuit for said tube coupled 95 thereto, an output circuit for said tube coupled thereto, means operable to change the period of said tuned circuit, and means controlled by the operation of said first-named means to a given position to establish each 100 of said couplings at a value appropriate to said changed period.

6. In combination, an electric discharge device, said device including output electrodes and input elements, an oscillation 105 circuit, a portion of said circuit being connected between said output electrodes and another portion being connected between said input elements, and a common means for changing the period of said circuit and changing the impedances of said portions to values corresponding to the changed period.

7. In combination, a vacuum tube, a tuned circuit, means including circuit connections connecting said tube and said circuit whereby oscillations are generated in said circuit by said tube, said tube having a cathode, an anode and an impedance varying element, a portion of said circuit being connected serially between said anode and cathode and a 115 portion of said circuit being connected between said cathode and element, switching means for changing the period of said circuit, and means under the control of said switching means for automatically establishing the impedance of each of said portions at a value appropriate to each position respectively of said switching means.

8. An oscillator comprising a space discharge device, a tuned circuit, an input cir- 130
